UNITED STATES PATENT OFFICE.

GUSTAVE ANTOINE RENAULT, OF PARIS, FRANCE.

CLASPING DEVICE FOR ARTICLES OF APPAREL.

1,401,556.

Specification of Letters Patent. Patented Dec. 27, 1921.

Application filed May 27, 1919. Serial No. 300,203.

To all whom it may concern:

Be it known that I, GUSTAVE ANTOINE RENAULT, maker, a citizen of the French Republic, residing at Paris, 37 Rue Reaumur, France, have invented certain new and useful Improvements in Clasping Devices for Articles of Apparel; and I do hereby declare the following to be a full, clear, and exact description of the invention, such as will enable others skilled in the art to which it appertains to make and use the same.

The present invention relates to a simple and convenient means for temporarily securing together parts of various articles of jewelry, such as chains, fobs, cuff links and the like.

Certain preferred forms of the invention are illustrated in the accompanying drawings wherein Figure 1 shows the male and female portions of a typical form in plan view, Fig. 2 is a transverse sectional view of the part C in Fig. 1, Fig. 3 is a view partly in plan and partly in section of the male member of a complete practical fastening made in accordance with the invention, Fig. 4 is a plan view of the lower plate of said male member, Fig. 5 is a plan view of a female member adapted for use with the male member shown in Figs. 3 and 4, and Figs. 6 and 7 are plan views of the male and female members of a modified form.

The general principle of the invention is typically exemplified in Figs. 1 and 2. If a flat member A having a non-circular opening B (preferably oblong) is fastened to one end of a chain E and the opposite end of the chain is furnished with a button or plate C having such a form in plan as permits it to pass through the opening B in one angular position but not in another, the parts A and C become respectively the female and the male members of a typical fastening embodying the principle of this invention.

It will usually be preferable, of course, to make C of the same shape in plan as the elongated opening B and just a little smaller, so that it will pass through easily. Having been passed through, the part C can be turned into the position shown in dotted lines in Fig. 1, and, if held in this position, the two parts secured respectively to A and C will remain fastened together. To unfasten them it is only necessary to bring C into registry with the opening B. The part C can be given almost any desired shape in cross section; as, for instance, the form

shown in Fig. 2. The only essential point in this connection is that the bottom shall be of a form to permit rotation of the part C over the female member A. A flat surface 60 here will usually be adopted.

Figs. 3 and 4 illustrate one practical form in which the above principles can be carried out.

The male member comprises a gem a 65 mounted upon a flat plate b, constituting a button which is provided with a pivot c, and having fastened thereto a flat guard-plate d preferably cut out as shown at e (for lightness) leaving a middle rib f. This rib 70 has an opening g through which passes the pivot pin c with a revoluble fit. Beneath the plate d, a small rivet or nut h is fixed to the end of the pivot pin c, and a ratchet wheel i with wide shallow rounded teeth 75 is welded or brazed onto the pivot pin so as to lie flat against the guard-plate d. Two spring pawls j and k are fixed each at one of its ends l and m to the rib f, while their free ends rest on the ratchet pinion i, 80 so as to prevent accidental turning of the button, while permitting it to be turned purposely by the fingers.

The female member of the clasp or fastening comprises a plate o having an elongated opening n and is fixed to the chain p or other part to be fastened. The button a is preferably of the same shape as the opening n and a little smaller, so that it can be pushed through this opening and then 90 turned into the desired locking position, in which position it will be held by the ratchet i and the pawls j and k. In this position, the plate n will occupy the space between the button a and plate d, and therefore the space 95 r between these parts should be a little greater than the thickness of the plate o.

This last named plate, and the button co-operating with it, may be given a great variety of forms. For instance, the button 100 might be a ring such as is shown in Fig. 6, having small projections q. The female member would then be a ring (as in Fig. 7) just large enough to let the button pass through it, and having notches or recesses u 105 adapted to admit the projections q in one position of the two rings. Upon revolving the button, the projections q would cease to register with the notches u, and the fastening would be accomplished.

What is claimed is—
In a fastening for the general purposes

described, a female member having a non-circular opening, and a male member comprising a guard-plate, a button adapted to pass through said opening in one angular position but not in another, said button being revolvably mounted on said guard-plate, and means tending to prevent the accidental turning of said button on said guard-plate, the button on the male member hav-

ing a pivot pin furnished with a ratchet 10 pinion, and resilient pawls carried by the guard-plate and bearing against said pinion.

In testimony whereof I affix my signature in presence of two witnesses.

GUSTAVE ANTOINE RENAULT.
